UNITED STATES PATENT OFFICE.

JOHN O. CARREY, OF ST. LOUIS, MISSOURI, ASSIGNOR TO C. & C. ENGINEERING CO., INC., OF ST. LOUIS, MISSOURI, A CORPORATION OF MISSOURI.

COMBINATION VALVE, DRIER, AND STRAINER.

Application filed August 25, 1926. Serial No. 131,459.

This invention relates to a combined pressure valve, drier, and strainer, the objects of the invention being to provide a device for use especially in connection with domestic refrigerating apparatus, whereby not only the flow of the refrigerant is automatically controlled by the pressure prevailing in the refrigerating system but the refrigerant is strained to prevent foreign substances from entering the system and is then filtered through suitable absorbent material to abstract moisture therefrom before admitting said refrigerant to the circulating system of the apparatus.

15 Further objects of the invention are to simplify the construction of a device of the class described so as to facilitate the assembly and construction thereof and eliminate the use of separate filters and strainers, thereby enabling the manufacture of such devices in an economical manner.

Other objects of the invention are to provide a valve device in which the flow of refrigerant is controlled by the difference in pressures prevailing in the outlet chamber of the device and the interior of the expandible member, which latter is disposed in said outlet chamber and operates suitable valve means for controlling the communication between the inlet and outlet chambers, and, further to provide means for regulating the pressure in said expandible member with respect to the pressure in the chamber in which said expandible member is located so as to render said device adjustable for operation at various pressures.

With these and other objects in view, my invention consists in certain novel features of construction and arrangement of parts, hereinafter more fully described and claimed, and illustrated in the accompanying drawings, in which—

Figure 1 is a vertical cross section through my valve device.

45 Figure 2 is a horizontal cross section taken on line 2—2 of Figure 1.

Figure 3 is a horizontal cross section taken on line 3—3 of Figure 1.

50 Figure 4 is a fragmental view of the device showing a modified form of a strainer.

In the operation of refrigerating apparatus, it is desirable to have automatic valve means in the circulatory connections of the apparatus for controlling the admission of

refrigerant thereto so as to maintain the refrigerant at predetermined pressures.

It is further desirable to circulate pure refrigerant only, as any water found in the refrigerant and permitted to enter coils of the system will be frozen, thereby clogging and stopping the circulation of the refrigerant and rendering the apparatus unfit for use.

To this end I provide a valve having an enlarged inlet chamber containing suitable filtering material which absorbs the moisture contained in the refrigerant so that only pure refrigerant leaves the inlet chamber of the valve.

Referring by numerals to the accompanying drawings, 10 indicates a casing consisting of a pot 11, the upper end of which is closed by a cover plate 12 which is secured to the flanged portion 11^a by suitable fastening devices 14. The interior of casing 10 is divided by a plate 15 into a receiving or inlet chamber 16 and a discharge or outlet chamber 17. Member 15 is flanged as indicated at 15^a and said flanged portion is interposed between flanges 11^a and 12^a, there being suitable packing 18 provided so as to hermetically seal the chambers 16 and 17. Chamber 16 which is located in the lower end of casing 10 is comparatively large and has arranged therein a screen or strainer 19 which is attached to member 15 and is spaced from the annular wall 11^b of pot 11, thereby providing an annular space 20 into which leads an inlet connection 21 through which the refrigerant is admitted to said chamber 16.

Strainer 19 is closed at the bottom and is provided with a central and upwardly disposed tubular portion 19^a, the upper end of which engages a boss portion 15^b depending from plate 15. The end of strainer 19 is preferably secured to the annular wall of member 15 by a band 22 and may be further secured thereto by soldering. Thus the only means of communication between the annular chamber 20 and inner chamber 24 formed by tubular extension 19^a is through strainer 19 and the annular space 25 formed in said strainer. This space is filled with suitable moisture absorbing material 26 such as fused crystals of calcium chloride so that the refrigerant passing through said space will filter through said material and any moisture contained in the refrigerant is absorbed thereby and only pure refrigerant is allowed to

enter chamber 24. Strainer 19 not only acts as a suitable container for the absorbent material but also prevents foreign substances which may have found their way into chamber 20 from entering space 25 and hindering the operation of the absorbent material contained therein.

Boss 15^b is provided with a valve opening 27 through which the refrigerant passes 10 from chamber 24 into discharge chamber 17. A discharge connection 28 opens into chamber 17 and conveys the refrigerant from said chamber. Valve opening 27 is controlled by a valve 29 which latter is operated by an expansible member 30 located in chamber 17 15 and operable to seat or unseat said valve 29 in accordance with the pressure prevailing in said chamber 17. This expansible member preferably comprises two diaphragm disks 31 and 32 sealed together at their annular edges as indicated at 34. The lower disk 31 has secured thereto a boss portion or enlargement 31^a in which is seated one end of a stem 35, while the other end of said stem extends 20 through valve opening 27 and has fixed thereto valve 29. The upper disk 32 is provided with an enlargement 32^a in which is fixed the lower end of a hollow stem 36 which extends upwardly a suitable distance above plate 12 25 and has its outer end opening into a chamber 37 formed in a bulb or reservoir member 38. This member is fixed to the upper end of stem 36 and preferably consists of two members 38^a and 38^b having interengaging annular 30 flanges which are preferably soldered together as indicated at 39 in order to hermetically seal chamber 37.

Opening into chamber 37 and seated in the upper member 38^b is a valve 40 having a valve 40 opening 41 opening to the atmosphere. This valve opening is closed by a spring pressed ball or closure member 42. By means of this valve 40 the pressure in chamber 37 and chamber 30^a of expansible member 30 can be regulated so as to provide the desired difference in pressure prevailing in chamber 30^a and chamber 17 in order to insure operation of valve 29 when the pressure in chamber 17 rises or falls below a predetermined degree. 45 In addition to controlling the pressure in chamber 30^a said expansible member 30 may be adjusted in vertical plane with respect to valve opening 27, stem 36 being provided with a threaded portion 44 which is screw-seated 50 in a threaded bore 45 of a boss 46 which latter is secured to plates 12 and extends upwardly therefrom. This boss 46 is exteriorly threaded for receiving a cap 47 there being suitable packing material 48 arranged between said 55 cap and the upper end of boss 46 so as to provide a fluid-tight seal for the stem 36. The bottom wall of pot 11 is provided with a screw plug 49 for providing access to chamber 24 and to valve 29.

60 When in use, inlet connection 21 has con-

nected thereto the discharge end 50 of the condenser of the refrigerating apparatus, and the outlet connection 28 has connected thereto the receiving end 51 of the expansion coil. Refrigerant is now admitted to chamber 20 and 70 passes through strainer 19 and filtering material 26 into inner chamber 24. Assuming now that valve 29 is unseated, the refrigerant will pass through opening 27 into chamber 17, thence through pipe 51 to the expansion 75 element of the refrigerating apparatus. When the pressure in chamber 17 reaches a predetermined degree, due to the expansion of the refrigerant, such pressure will cause expansible member 30 to collapse and as the 80 upper disk 32 thereof is held immovable by stem 36, lower disk 31 will be moved upwardly, thereby seating valve 29 and closing opening 27 so that no refrigerant can pass into chamber 17. The communication between 85 chambers 16 and 17 will be interrupted until the pressure in the latter is reduced to such an extent as to allow the pressure in chambers 30^a and 37 to expand member 30, thereby unseating valve 29. The pressure prevailing 90 in chamber 30^a and the communicating chamber 37 is fixed with respect to the pressure prevailing in chamber 17 and thereby causing expansible movement of member 30 and the consequent unseating of valve 29 95 whenever the pressure in chamber 17 falls below a predetermined degree. This fixed pressure in chamber 30^a can be varied by means of valve 40 so as to insure operation of valve 29 at the appropriate time and also 100 to enable the use of my improved valve device in conjunction with apparatus operating under various pressures.

If desired, chambers 30^a and 37 may be placed under vacuum or partial vacuum, 105 thereby rendering said device responsive to very slight pressure. Valve 30 is so constructed that when the connection is fitted to said valve to increase or decrease the pressure in chamber 37 valve 42 may be unseated by 110 said connection through bore 41. When proper pressure has been obtained in chamber 37, said valve 40 may be sealed by placing a drop of solder on said valve as shown in the drawing.

115 By placing the expansible member under predetermined constant pressure with respect to the chamber in which it is located, said expansible member will be operated in accordance with the difference in pressure between 120 said expansible member and said chamber to seat and unseat said valve. In this manner, the operation of the valve is effected by the opposing pressures and is not made dependent on the resiliency of springs or other mechanical means. This arrangement makes the valve device more sensitive to pressures and renders it positive in action as all danger of 125 breakage of springs or change in the resiliency thereof is eliminated. The use of the 130

bulb member on the outer end of the hollow stem provides a reservoir for receiving part of the fluid when the expansible member occupies retracted position and also provides means for regulating the fluid pressure in said expansible member.

In the modified form shown in Figure 4 strainer 19 is formed on the bottom with a beaded portion 19^b which spaces said bottom 10 from bottom wall of container 11 thus providing additional space 20^a so that the refrigerant can enter the strainer from the bottom as well as the sides. The beaded portion 19^b which is formed adjacent to the chamber 15 24 forms a close fit with the inturned flange of central boss 49^a and seats the joint therebetween so that the refrigerant has to pass through the absorbent material 26. The latter preferably consists of fused calcium chloride 20 but other material may be used if so desired.

A valve device constructed according to my invention is highly responsive to the pressure difference, has a wide range of adjustment, and is inexpensive to manufacture and maintain.

While I have shown the preferred form of my invention, it is to be understood that minor changes can be made and substituted 30 for those herein shown and described, without departing from the spirit of my invention.

I claim:

1. In a valve device for refrigerating apparatus the combination of a casing comprising a pot, a cover therefor, and a partition wall arranged in said pot and dividing the interior thereof into a lower inlet chamber and an upper outlet chamber, valve means for controlling the communication between said 35 chambers, a hollow expansible member disposed in said outlet chamber and connected to said valve means, said expansible member being maintained under a fixed predetermined fluid pressure with respect to the fluid pressure prevailing in said outlet chamber whereby said expansible member is actuated to open and close said valve means in a definite relation with the pressure prevailing in said outlet chamber, and automatically closed means 40 for varying said fixed fluid pressure in said expansible member.

2. A valve device for refrigerating apparatus comprising a casing having an inlet chamber and an outlet chamber, valve means 45 for controlling the communication between said chambers, an expansible member disposed in said outlet chamber and connected to said valve means, said expansible member being under a fixed predetermined pressure 50 with respect to the pressure prevailing in said outlet chamber, whereby said expansible member is actuated to open and close said valve means in a definite relation with the pressure prevailing in said outlet chamber, 55

60 a hollow stem leading from said expansible

member exteriorly of said casing, and valve means for closing the outer end of said hollow stem and providing communication with said expansible member for regulating the pressure prevailing therein.

70

3. A valve device for refrigerating apparatus comprising a casing having an inlet chamber and an outlet chamber, valve means for controlling the communication between said chambers, an expansible member disposed in said outlet chamber and connected to said valve means, said expansible member being under a fixed predetermined pressure with respect to the pressure prevailing in said outlet chamber, whereby said expansible member is actuated to open and close said valve means in a definite relation with the pressure prevailing in said outlet chamber, a bulb member fixed to the outer end of said hollow stem and having the latter opening 80 thereinto, and normally closed valve means in said bulb member for affording communication with said expansible member to vary the fixed pressure thereof.

75

4. In a refrigerating apparatus, the combination with the condenser element and expansion element thereof, of a casing comprising an open top container, a partition wall arranged therein in sealed engagement therewith and dividing the interior thereof into 90 a lower inlet chamber connected to said condenser element and into an upper outlet chamber connected to said expansion element, a cover in sealed engagement with said partition wall for closing said upper chamber, 95 valve means for controlling the communication between said chambers, and moisture-absorbing chemical arranged in said inlet chamber for extracting moisture from the refrigerant before the latter is admitted to said outlet chamber.

100

5. A differential pressure valve comprising in combination a casing having an inlet chamber and an outlet chamber, valve means for controlling the communication between 110 said chambers, an expansible member arranged in said outlet chamber and sealed relative thereto, said expansible member being maintained under a predetermined fluid pressure with respect to the pressure in said outlet chamber, whereby the difference in pressures in said expansible member and said outlet chamber will actuate said expansible member to open or close said valve means, a hollow stem fixed to said expansible member and adjustably mounted in said casing for adjusting said expansible member in vertical plane relative to said valve means, and a hollow enlargement on the outer end of said stem and communicating with the interior of said 115 expansible member for forming a reservoir for receiving the excess fluid from said expansible member.

120

6. A differential pressure valve comprising in combination a casing having an inlet 130

- chamber and an outlet chamber, valve means for controlling the communication between said chambers, an expansible member arranged in said outlet chamber and sealed 5 relative thereto, said expansible member being maintained under a predetermined fluid pressure with respect to the pressure in said outlet chamber whereby the difference in pressures in said expansible member and said 10 outlet chamber will actuate said expansible member to open or close said valve means, a hollow stem fixed to said expansible member and adjustably mounted in said casing for adjusting said expansible member in vertical 15 plane relative to said valve means, a hollow enlargement on the outer end of said stem and communicating with the interior of said expansible member for forming a reservoir for receiving the excess fluid from said 20 expansible member, and valve means in said enlargement to establish communication between said expansible member and the exterior of said casing, said valve means being normally hermetically sealed.
- 25 7. In a device of the class described, the combination of a sealed casing comprising a container having a flanged open top, an annularly flanged partition disposed in said container and dividing the interior thereof into 30 a lower inlet chamber and an upper outlet chamber, the flange of said partition having a sealed joint with the flange of said container, an annularly flanged cover having a sealed joint with said partition and closing 35 the upper end of said outlet chamber, said chambers being provided respectively with inlet and outlet connections adapted to be connected to a condenser element and an expansion element, respectively, and fused crystals of calcium chloride arranged in said 40 inlet chamber in the path of travel of the refrigerant passing from one of said elements to the other whereby moisture contained in said refrigerant is absorbed by said chemical and prevented from circulating with said 45 refrigerant.
8. In a device of the class described, the combination of a casing, comprising a container provided with an annularly flanged open top, an annularly flanged partition 50 member having its intermediate portion depressed so as to occupy position spaced from said top and dividing the interior of said container into a lower inlet chamber and an upper outlet chamber, whereby said casing is 55 adapted to be connected to the circulating system of a refrigerating apparatus between the condenser and expansive elements thereof; pressure operated valve means for controlling communication between said chambers, a screen member arranged in said inlet chamber in spaced relation therewith, and a moisture absorbent chemical held by said screen member in the path of travel of the refrigerant passing through said casing, where- 60 by water contained in the refrigerant is absorbed by said absorbent chemical and prevented from entering said expansion element.
- In testimony whereof I hereunto affix my signature this 21st day of August, 1926.

JOHN O. CARREY.
